UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

SHUTTLE-FEELER AND FILLING CLAMPING AND PARTING MEANS.

Application filed October 22, 1923. Serial No. 669,892.

To all whom it may concern:

Be it known that I, ALONZO E. RHOADES, a citizen of the United States, and resident of Hopedale, county of Worcester, State of Massachusetts, have invented an Improvement in Shuttle-Feeler and Filling Clamping and Parting Means, of which the following description, in connection with the accompanying drawing, is a specification, like characters on the drawing representing like parts.

This invention relates to the shuttle feeler mechanism and the mechanism for clamping and parting the filling in an automatic filling replenishing loom.

The main object of the invention is to provide a construction which shall be mounted and operated above the lay so that the parts may be readily accessible for replacement or repair and other purposes.

The objects and nature of the invention will appear more fully from the accompanying description and drawings and will be particularly pointed out in the claims.

In the drawings:

Fig. 1 is an end elevation partially in vertical cross section, with the main portion of the loom broken away and with only those parts directly concerned with the present invention shown and looking from the inside of the loom toward the loom side.

Fig. 2 is a detail in front elevation and on a smaller scale of the parts directly concerned with the present invention.

The invention is shown as embodied in its preferred form in an automatic filling replenishing loom of the Northrop type and as that type of loom is well known and familiar to those skilled in the art it will only be necessary to illustrate and describe those portions of the loom directly concerned with the present invention.

The loom frame is shown as comprising the end or side portions 1 connected at the front by the breast beam 2. The lay 3 on which reciprocates the shuttle 4 is carried by swords 5 and swings toward and from the breast beam. At the replenishing side of the loom a magazine or hopper stand 6 is mounted and carries a suitable magazine or hopper, in this case of the rotary type, in which is the supply of fresh filling carriers 7.

When the filling in the running shuttle

suitable mechanism is put in motion to transfer a fresh filling carrier from the magazine or hopper into the shuttle and to eject therefrom the filling carrier to be abandoned. In the Northrop type of loom illustrated a controller rod 8 extends along at the front of the breast beam and this rod is rocked upon the call for filling replenishment by suitable mechanism. Thereupon the arm 9 is elevated against the tension of the spring 10 and swings rearwardly the arm 11 pivoted at 12 on the loom frame. This arm 11 carries rigidly connected thereto a slotted arm 13 which, as the arm 11 swings rearwardly, acts to raise a dog 14 into the path of a bunter 15 carried by the lay. As the lay beats forward after the call for filling replenishment this bunter 15 strikes the dog 14 and the dog 14 being pivoted to the shorter arm 16 of the trans- 70

parting means it is necessary for the shuttle 5 feeler to have in addition to its forward and rearward movement a lateral movement so that as the shuttle feeler moves forwardly with the filling end extending from the fell 10 held clamped in the filling clamping means this end will not be stretched and broken. The shuttle feeler shank 20 is therefore provided at its upper end with an elongated hub 21 which is mounted to pivot and slide laterally on a stud 22 projecting from the hopper stand. The required lateral movement of the shuttle feeler is effected by a cam mounted on the hopper stand and co- 15 operating with the shank of the shuttle feeler. In the construction illustrated a bracket 23 is bolted to the hopper stand and is provided with a projecting flange 24 in which is formed a cam slot 25. A pin 26 projects downwardly from a shouldered portion of the shank 20 and rides in the slot 25.

The forward and rearward movement of the shuttle feeler is secured by a connection 25 between it and the arm 11 already described. For this purpose a block 27 is pivoted at 28 on the arm 29 projecting rearwardly from the shank 20, a similar block 30 is pivoted at 31 on the upper end of the arm 11 and a rigid flat bar 32 is pivoted in slots in the blocks 27 and 30 on pins 33 extending at right angles to the pivots 28 and 31. Thus there is provided between the arm 11 and the shuttle feeler shank a connection which 35 will transmit thrust and at the same time will permit the required relative lateral movement of the shuttle feeler.

The filling clamping and parting means comprises the usual rigid cutting and clamping blades secured to the lower end of the shuttle feeler shank and the movable cutter blade 34 pivoted at 35 on the shuttle feeler. This blade is provided with a depending tail 36 and a laterally extending pin 37 by 45 which it is operated. When the shuttle feeler is moved rearwardly upon the call for filling replenishment carrying with it the filling clamping and parting means the movable blade 34 must be swung to open 50 position so as to enable the filling end to be carried between the blades upon the beat up of the lay and as this beat up takes place the movable blade 34 must be closed to clamp and part the filling. The closing movement 55 is effected by the lay striking against the depending tail 36. The opening movement is effected by a switch cam cooperating with the pin 37. This switch cam 38 is shown as

of triangular shape and pivoted at 39 to a supporting bracket 40 mounted above the lay and shown as bolted at 41 to the top of the breast beam. The lower portion of the switch cam 38 is positioned laterally away from the support 40 and in the path of the pin 37. As the shuttle feeler moves rearwardly the pin 37 acting against the inclined face of the switch cam 38 swings the movable blade 34 to open position. Upon the forward movement of the shuttle feeler the pin 37 engaging the vertical face of the switch cam swings it out of the way and passes beneath it.

It will thus be seen that a very simple rigid and durable form of construction of these important parts of the loom is provided. The shuttle feeler with its connected filling and clamping and parting means, the cam for giving the lateral movement to the shuttle feeler and the switch cam and its support for operating the filling clamping and parting means are all mounted well above the lay and in a position where they are readily accessible for replacement and repair.

Having thus described the invention, what is claimed as new, and desired to be secured by Letters Patent, is:

1. An automatic filling replenishing loom comprising a frame, a lay, a hopper stand and hopper for the supply of fresh filling carriers, a shuttle feeler having an upwardly extending shank mounted at its upper end to swing forwardly and rearwardly and to slide laterally on the hopper stand at a point above the lay, a cam on the hopper stand cooperating with the shank to effect the said lateral movement, filling clamping and parting means carried by the shuttle feeler, an arm mounted at its lower end on the loom frame at a point below the lay to swing forwardly and rearwardly, a connection between the arm and the shuttle feeler acting to transmit thrust and permit relative lateral movement therebetween, and means for swinging the arm rearwardly upon the call for filling replenishing.

2. An automatic filling replenishing loom having the construction defined in claim 1, together with a switch cam and a support therefor mounted on the loom frame above the lay, the said switch cam acting to open the filling clamping and parting means during its rearward movement.

In testimony whereof I have signed my name to this specification.

ALONZO E. RHOADES.
